J. Knowles.
Let-Off Loom.

N° 209.

Patented Nov. 8, 1853.

UNITED STATES PATENT OFFICE.

JONATHAN KNOWLES, OF COHOES, NEW YORK.

LOOM.

Specification of Letters Patent No. 10,209, dated November 8, 1853.

To all whom it may concern:

Be it known that I, JONATHAN KNOWLES, of Cohoes, in the county of Albany and State of New York, have invented a new and useful Improvement in Looms, of which the following is a full, clear, and exact description, reference being had to the accompanying drawings, which make part of this specification, and in which—

10 Figure 1 represents an end elevation of the frame lay and let off mechanism of a common power loom with my improvements applied thereto; Fig. 2, a top view of the tension roller and its guides; and Fig. 3 a 15 back view of the same.

My invention and improvement relates to the mechanism for unwinding or letting 20 yarn off the warp beam as is required by the progress of the weaving, and it consists in arranging what is termed the tension or 25 whip-roll, which is hung in the usual manner upon the arms of a vibrating lever, to roll up and down inclined guides in its vibrations to accommodate itself to the length 30 of the yarn unwound from the warp-roll. This tension-roll moves forward toward the breast beam as the warp is taken up by the weaving, until it arrives at a position where it puts into action the mechanism for turning 35 the warp beam to let off warp. As the warp is let off, the roll is forced back again by the action of a weight to take up the slack and maintain the tension of the warp, the roll is thus kept constantly oscillating 40 forward and back and the weight which produces the tension so kept rising and falling, and as a very moderate degree of tension upon each one of the numerous warps, would in the aggregate counterbalance a heavy

40 weight, the constant rising and falling of this weight would produce a series of surges and strains, highly objectionable and prejudicial. With a view to produce the requisite tension upon the warps with a light weight and without adding to the complexity of the moving parts of the loom I have applied an incline guide (a) to the inside of each of the standards between which the whip roll plays, for the journals of the roll to rise on as they are carried toward the 45 breast beam. These inclined guides turn on pivots (c) and are adjustable by means of set-screws (d) that pass through slots in the standards to various degrees of inclination to alter the strain upon the warps as may be 50 required, as the strain increases, in the same ratio that the inclination of the guides increase and vice versa; therefore, instead of employing a heavy weight to strain the warp tightly, it is merely necessary to increase the 55 inclination of the guides.

I have not given a particular description of any of the parts of the loom except the inclined guides which I have added, as the other parts are all well known and in common use.

60 What I claim as my invention and desire to secure by Letters Patent, is—

The combination of inclined guides with the whip roll for the purpose of graduating 70 the tension of the warps substantially as herein set forth.

In testimony whereof I have hereunto subscribed my name.

J. KNOWLES.
